UNITED STATES PATENT OFFICE.

KATHERINE E. BURNS, OF NEW YORK, N. Y., ASSIGNOR TO FRANKLIN SIMON & CO., INC., OF NEW YORK, N. Y., A CORPORATION OF NEW YORK.

DESIGN FOR A DRESS.

Application filed July 29, 1927. Serial No. 22,951. Term of patent 3½ years.

To all whom it may concern:

Be it known that I, KATHERINE E. BURNS, a citizen of the United States, and a resident of the city of New York, borough of Manhattan, in the county and State of New York, have invented a new, original, and ornamental Design for a Dress, of which the following is a specification, reference being had to the accompanying drawing, forming part thereof, wherein the design is distinguished by ornamental stripes around the wrist sections of the sleeves, around the center of the garment, and along the front

edges of the upper part of the garment, these stripes being formed with a center portion and edge portions of a contrasting color.

Figure 1 is a front perspective view of a dress, showing my new design the same being shown on a figure indicated by dotted lines.

Figure 2 is a detail rear view of one of the cuffs shown in Figure 1.

I claim:

The ornamental design for a dress, substantially as shown and described.

KATHERINE E. BURNS.
